UNITED STATES PATENT OFFICE.

NORMAN DODGE, OF EAST ORANGE, NEW JERSEY, ASSIGNOR TO MERGENTHALER LINOTYPE COMPANY, A CORPORATION OF NEW YORK.

TYPOGRAPHICAL MACHINE.

1.117,348.

Specification of Letters Patent.

Patented Nov. 17, 1914.

Application filed December 16, 1913. Serial No. 806,984.

To all whom it may concern:

Be it known that I, NORMAN DODGE, a citizen of the United States, residing at East Orange, in the county of Essex and State of New Jersey, have invented certain new and useful Improvements in Typographical Machines, of which the following is a specification, reference being had thereto in the accompanying drawing.

- 10 My invention relates to typographical machines, such as linotype machines of the general organization represented in Letters Patent of the United States, No. 436,531 and No. 436,532, to O. Mergenthaler, where-
15 in circulating matrices are released from a magazine in the order in which their characters are to appear in print and then as-
sembled in line, the composed line trans-
ferred to the face of a mold, the mold filled
20 with molten metal to form a slug or linotype against the matrices which produce the type characters thereon, and the matrices thereafter returned through distributing
mechanism to the magazine from which
25 they started. More particularly, it relates to improved means whereby the machine is readily adapted to handle matrices formed with plural characters of materially different sizes. In such machines, the composed
30 line is presented to the casting mechanism by a carrier, ordinarily known as the first elevator", the presenting movement of which may be varied in order to bring the line into appropriate relation to the mold,
35 and thus to permit the employment of mat-
rices having characters of different extent as may be desired. For instance, in the use of large characters for head-letters, it is customary to present the elevator at a
40 higher level from that at which it is pre-
sented with ordinary characters, in order to insure their correct alinement with the mold slot. Devices somewhat similar to those just mentioned are described in United
45 States Letters Patent to John R. Rogers, No. 890,177. It is also customary in the art to equip linotype machines with double or Janus-faced matrices, that is to say, mat-
rices formed with characters in their oppo-
50 site edges, in combination with an assem-
bling mechanism and reversing means, whereby a matrix may be delivered to the line with one or another of its characters in operative position at will. Such reversing

means are illustrated for instance in United States Letters Patent to Holbourns & Longhurst, No. 951,948.

The specific embodiment of my invention permits the actuation of the means for ar-
resting the first elevator in different posi-
tions simultaneously with the adjustment
of the matrix-reversing means. In this way
I adapt the machine to the employment of
Janus-faced matrices formed in their oppo-
site edges with characters of materially dif-
ferent extent, this result being secured with-
out special attention or care on the part of
the operator, and without the liability to
imperfect results which would arise in the
event that the several devices are not cor-
respondingly adjusted.

In the accompanying drawings, I have shown my invention in preferred form and by way of example, and as applied to the style of machine already mentioned, but ob-
viously many changes and variations may be made therein, and in its mode of appli-
cation, which will still be comprised within
its spirit. Generally speaking, I desire it to
be understood that I do not limit myself to
any specific form or embodiment, except in
so far as such limitations are specified in
the claims.

Referring to the drawings: Figure 1 is a front perspective view of a portion of a linotype machine having my invention applied thereto; Fig. 2 is a front elevation thereof; and Fig. 3 illustrates a Janus-faced matrix of the kind employed in the machine.

As is usual, the matrices are released by the manipulation of the keyboard R and de-
livered to the assembler belt S, from which they pass to the assembler T. After the line is composed, the assembler is raised and the line transferred therefrom through the in-
termediate channel W into the first elevator E, by which it is presented to the casting de-
vices. When Janus-faced matrices are em-
ployed, their position is controlled by suit-
able reversing means, such for instance as the device A, which receives them from the belt S and through which they pass into the assembler T. As in the said Holbourns & Longhurst patent, this device is provided with two throats, one a straight or plain channel to deliver the matrices unreversed, and the other a tortuous or rifled channel to reverse them in their passage to the line. In

the drawings herein the upper or reversing channel A^1 is shown in operative relation to the other parts.

In the present instance the device A is 5 slidably mounted in the frame and is normally forced upward by the spring A^2 to bring the straight or plain channel into operation, but it may be moved in the opposite direction to bring the rifled or reversing 10 channel into position by the finger key B and the connected link or riser C. The key B is located in convenient proximity to the keyboard R, and the link C is suitably inclined and formed to engage the end of the 15 pivoted arm D, the link being preferably provided with a roller C¹ to bear upon the nose or outer end of the arm. The arm D passes transversely across the upper portion of the frame of the reversing device A, and 20 is located above the stud A^{10} on the latter, the arm being formed with a plurality of notches D¹ to engage the stud in the several operative positions. Normally the spring A² holds the device A, arm D, link C, and 25 key B in their uppermost positions, but when the key is actuated, the link C depresses the arm and the reversing device so as to bring the channel A^1 into operation, as indicated in the drawings. The key B may 30 then be engaged with a notch or cut B¹ in the framework to hold the several elements against the tension of the spring A². The parts so far described are or may be of any 35 ordinary construction, and in themselves constitute no part of my present invention.

Fig. 3 illustrates a double or Janus-faced matrix X formed with intaglio characters X¹ and X² on its opposite edges. It will be noted that the characters X¹ are of the ordinary size, whereas the character X² is much larger or of greater extent, such for instance as would be required for a head-letter. Through the reversing means previously described, either edge may be brought into 45 operative position, but due to the difference in the size of the characters, it is necessary that they should be presented in different relations to the casting mechanism. This result I secure by means also operated from 50 the key B, the elements being so arranged that when the reversing device is adjusted, the throw of the presenting means is simultaneously and correspondingly adjusted.

As in the ordinary construction, the matrices are supported in the first elevator E and are thereby presented in the casting position. The extent of movement of the elevator is governed by the contact of a screw E¹ thereon with the vise cap F; and the 55 starting rod, ordinarily termed the "automatic", which controls the clutch mechanism, is actuated by a second screw also carried by the elevator (as indicated by dotted lines in Fig. 2), the depression of the rod 60 being necessary to permit the casting oper-

ation. In ordinary circumstances, such as in connection with the characters X¹ of the matrices X, the elevator descends until the screw E¹ contacts directly with the vise cap. If the machine be adjusted to reverse the 70 matrices and use the characters X², it is necessary to arrest the elevator at a higher point, and a piece or slide G is therefore employed which may be interposed between the screw and the vise cap, which relations are 75 shown in Figs. 1 and 2. In order similarly to effect the operation of the starting rod, when the elevator stops in its higher position, the sliding stop G is provided with a connected member G¹, so that when the slide 80 G is brought into operation, the member G¹ is located above the rod (see Fig. 1) so that the latter is properly moved to permit the casting. The interponents G and G¹ are shifted by the sliding link H, which is provided with the spring H¹, whereby the parts are normally held in and returned to inoperative position. The link H is connected by the elbow lever J, link H, and lever L to the vertical slide M, the latter being formed 90 with the slot M¹ through which the key lever B projects and whereby the position of the slide is controlled.

When the key B is actuated, as shown in the drawings, it effects the depression of the 95 device A in the manner previously described. Simultaneously the key contacts with the bottom of the notch M¹ and moves the slide M downwardly, and through the connections above set forth, shifts the interponents G and G¹ to their operative position against the force of the spring H¹. In this relation of the parts, the upper or rifled throat A¹ of the device A acts to reverse the matrices X so as to bring the large 100 or extended characters X² into operation, and the elevator is arrested in its higher position so as to effect the proper relation of the extended characters to the other casting devices. When the key B is released and returned to its upper or normal position, the spring A² shifts the device A upwardly and brings its straight or plain channel into operation; and simultaneously the release of the slide M permits the spring 105 H¹ to move the interponents G and G¹ to their normal or inoperative position. In other words, at this time the machine is 110 adjusted so as to deliver the matrices X with the ordinary characters X¹ in operative position, and to permit the full descent of the elevator E so that the matrices will be presented thereby in their usual relation to the mold. It will be seen that in this way and 115 by the operation of a single key, I control both the selection of the characters on the opposite edges of the matrices and the adjustment of the first elevator to the corresponding casting position.

It will be understood that the particular 120

devices described have been selected principally for the purpose of convenient illustration, and specifically as representing the manner in which my invention may be embodied in a machine adapted to employ 5 Janus-faced matrices formed with ordinary characters in connection with head-letter characters. Obviously, however, many modifications and alterations therein, and in its 10 mode of adaptation, will suggest themselves to those skilled in the art, without departure from its scope.

Having thus described my invention, its 15 construction and mode of operation, what I claim and desire to secure by Letters Patent of the United States, is as follows:

1. In a typographical machine, the combination of means for presenting a matrix line in a plurality of relatively different casting 20 positions, matrix-reversing means, and a common device for controlling the operations of both said means.

2. In a typographical machine, comprising 25 matrices each formed with a plurality of characters, the combination of means for assembling the matrices in line with one or another of the characters in operative position, means for presenting the matrix line in a plurality of relatively different casting 30 positions, and a common device for controlling the operation of both said means.

3. In a typographical machine, comprising 35 matrices formed with head-letter characters, the combination of means for assembling the matrices in line with such characters in operative position, a carrier for presenting the line to the mold, and stop devices controlled by the assembling means 40 for limiting the presenting movement of the carrier.

4. In a typographical machine, the combination of a matrix carrier movable to and

from the mold, means for determining the position of the carrier with relation to the mold, matrix-reversing means, and a common device for controlling the operation of 45 both said means.

5. In a typographical machine, the combination of a matrix carrier movable to different positions with relation to the mold, 50 matrix-reversing means, and devices operated by the matrix-reversing means for controlling the extent of movement of the carrier.

6. In a typographical machine, the combination of a matrix carrier movable to and 55 from the mold, a movable stop device to arrest the movement of the carrier, a movable matrix-reversing chute, and connections between said chute and stop device whereby 60 the movement of one of them to operative or inoperative position will effect the corresponding movement of the other.

7. In a typographical machine, the combination of a matrix carrier movable to and 65 from the mold, a matrix-reversing chute movable to operative and inoperative position, and a movable stop device operated by said chute to arrest the movement of the carrier. 70

8. In a typographical machine, the combination of a matrix carrier movable to and 75 from the mold, a movable stop device to arrest the movement of the carrier, a movable matrix-reversing chute, and a finger key connected to both said chute and said device for controlling their movements.

In testimony whereof I have affixed my signature in presence of two witnesses.

NORMAN DODGE.
